CALL-DISTRIBUTING SYSTEM.

1,310,226.

Specification of Letters Patent. Patented July 15, 1919.

Application filed July 14, 1917. Serial No. 180,633.

To all whom it may concern:

Be it known that I, SAMUEL B. WILLIAMS, Jr., a citizen of the United States, residing at Brooklyn, in the county of Kings and State of New York, have invented certain new and useful Improvements in Call-Distributing Systems, of which the following is a full, clear, concise, and exact description.

- 10 This invention relates to a telephone call distributing system of the type in which the calls originated by the telephone lines of the exchange are automatically distributed to the operators' positions that are available. 15 for receiving them. In complex systems of this character, abnormal conditions sometimes arise that tend to prevent the proper and prompt extending of the circuits of calling lines to the operators' positions. It is 20 the principal object of this invention to provide an organization in which such abnormal conditions, when they arise, will be taken care of and prevented from interfering with the proper operation of the system. 25 Generally stated, the present system provides a plurality of operators' positions each equipped with a number of plug-terminated connecting circuits for completing connection with called subscribers' lines. The connection 30 between these connecting circuits and the calling subscribers' lines is effected through the medium of a number of finder circuits each of which has an automatic switch at one end for finding and connecting 35 with any subscriber's line that may be calling, and an automatic switch at the other end for selecting an available operator's position, and then connecting with an idle connecting circuit at that position. The selection 40 of an available operator's position is controlled by operator's selecting apparatus common to all of the finder circuits and all of the operators' positions.

In the normal operation of the system the potential which identifies any of the lines as a calling line is automatically withdrawn when the finder circuit makes connection with that line. If through any fault of the apparatus that potential is not withdrawn, 45 the extension of the line to an operator's position may give rise to difficulties. One of the objects of the present invention is to prevent the line under such conditions from

being extended. Another object is to make the disconnection of the finder circuit from the calling line subject to the return of the connecting circuit to its normal condition so that the finder circuit may be held and identified, or a characteristic signal given, in case it is not operating properly. Another object of the invention is to provide means for preventing the finder circuit from proceeding to its operator's selecting stage until the operator's selecting apparatus is in readiness to coöperate with the finder circuit selecting switch. Another object is to provide means for rendering all of the connecting circuits of an operator's position instantly and temporarily unselectable when one of them has been selected by a finder circuit. Other objects of the invention will appear in connection with the description of the organization which follows.

The preferred embodiment of the system of the invention is illustrated in the accompanying diagrammatic drawing in which Figure 1 shows two groups of lines with two line finder switches for making connection therewith, together with the associated circuits and apparatus through the medium of which the lines control the switches; Fig. 2 shows one finder circuit complete, and enough of two other finder circuits to illustrate the relationship between them; Fig. 3 shows two cord selector switches of one frame with their associated selection controlling apparatus and circuits, together with similar apparatus and circuits for the cord selector switches (not shown) of another frame and Fig. 4 shows the position apparatus and one of the connecting cord circuits of one operator's position and indicates the position apparatus and a connecting cord circuit of another position; also one of the called lines with which the cord circuit may be connected. The figures taken together, and arranged side by side in the order indicated by the lines that extend to the margins of the sheets, illustrate as much of a complete organization as is necessary to gain an understanding of the construction and mode of operation of the system.

Two telephone lines are indicated in each of the two groups shown in Fig. 1, it being understood that each group may comprise a large number of such lines. The practice is

to give the finder switch brushes access to the terminals of five hundred lines, these lines being arranged in ten groups of fifty lines each. Each of the lines has associated with it at the central office a line relay 12, and a cut-off relay 11. Each line is also provided with one or more spring jacks 14 by means of which connection may be made with the line when it is a called line. The 5 lines represented as calling lines in Fig. 1 and the line shown as a called line in Fig. 4 may be lines of the same sort, similarly equipped and located at the same exchange; or the lines may be located at different offices. In the present instance, the called line shown in Fig. 4 is indicated as being provided with connections by means of which it may have control over finder switch mechanism in the manner illustrated in connection with the lines of Fig. 1. Each group 10 of lines, LG and LG', has associated with it certain group apparatus consisting of two relays 19 and 24, a common protective relay 250, and a timing sequence switch 100. There is also provided apparatus common to 15 all of the line groups, comprising the relays 22, 23 and 33. The groups of lines have access to groups 20 of connecting circuits through the medium of finder circuits F, F', and F², which terminate upon the brushes of pairs of finder switches of which two sets, LF and CS and LF' and CS', are shown. Each of the groups of connecting circuits is associated 25 with a particular operator's position, of which the apparatus of one is shown at O and the apparatus of the other is partially shown at O'. In the particular system illustrated, it is the practice to provide each operator's position with twenty-five connecting 30 circuits extending to multiplied groups of terminals upon the cord selector switches, and to give the brushes of each cord selector switch access to the terminals of twenty such groups of connecting circuits. But one of 35 the connecting circuits is shown complete, the other connecting circuits in the associated group and in the other groups being similarly organized and connected. Multiple 40 connections of the connecting circuit with the terminals of the cord selector switches are shown in the case of the connecting circuit that is completely illustrated; and in like manner multiple connections of the telephone line with the terminals of the line finder switches are shown 45 in the case of the line that extends from station A. The multiple connections that exist between corresponding sets of switch terminals and the other connecting circuits and telephone lines are omitted to avoid confusing the drawing.

A number of groups of cord selector switches like the group illustrated in Fig. 65 3 may have access to the same groups of con-

nected circuits and their corresponding operators' positions. This is indicated in Fig. 3. Each of the groups of cord selector switches has associated with it certain selection controlling apparatus, that associated with the cord selector switches shown in Fig. 3 appearing under the caption "Frame 2," and that associated with the cord selector switches of the other group that is not shown appearing under the caption "Frame 1." The selection controlling apparatus for each frame or group of cord selector switches comprises a set of relays 77, 93 and 94 for each operator's group, CG, CG', to which the cord selector has access, 80 and a group of relays 52, 54, 55, 61, 63 and 254 common to all of the first mentioned groups.

As the line finder switches LF and LF', and the cord selector switches CS and CS' in themselves are not novel, they are shown merely diagrammatically. These switches may be substantially like the switch illustrated and described in the patent to James L. McQuarrie, No. 1,177,044, issued March 28, 1916. The line finder and cord selector switches are alike in all substantial respects. Each comprises a longitudinally movable shaft 1 carrying as many sets of brushes 2 as there are groups of stationary terminals 95 to be engaged. To move the shaft up, an extension at the lower end of the shaft is brought into engagement with the constantly rotating power member 3 by means of an idler wheel operated by the up-drive magnet 32; and to move the shaft down, the extension is brought into engagement with the power member 4 by means of an idler wheel operated by the down-drive magnet 62.

Normally the brushes of each of the sets 100 2 are held apart, so as to clear the associated terminals, by means of a separating cam 5 located between the innermost brushes of the set. The cam 5 is rotatably mounted, and when rotated in one direction, releases the brushes and permits them to engage the associated terminals. The tripping or releasing of the brushes is controlled by a number of trip-magnets 16, 17. Each of 110 these when energized rotates an associated trip rod 6 that extends transversely to the switch shafts 1 and carries as many tripping yokes 7 as there are finder switches in the group. The trip rod, in rotating, brings 115 all of its tripping yokes 7 into position to operate the brush controlling cams 5 of the corresponding sets of brushes on all of the switches, so that whichever of the finder switches is caused to move up has that set 120 of brushes tripped that corresponds with the particular trip magnet 16, 17, that is at the time energized. When the finder switch that has been in use is returned to its normal position, any of the associated controlling 125 130

cams 5 that has been tripped is engaged and rotated in a reverse direction to separate its switch springs again and thus render them inactive.

5 Each of the line finder and cord selector switches has associated with it a commutator 8 which comprises a number of stationary commutator segments and a set of movable brushes carried at the top of the switch

10 shaft 1 and co-operating with the stationary segments. This commutator serves to make and break a number of controlling circuits in the various stages of the upward movement of the switch shaft.

15 For controlling the circuits of the organization, there are employed a number of sequence switches which are shown at different points and are designated 100, 200, 300 and 400, respectively. These sequence switches

20 may be of the type disclosed in Patent 1,127,808, issued February 9, 1915, to Reynolds and Baldwin. Each consists of an electromagnetically controlled motor or driving mechanism and a number of associated

25 switch cams. The switch cams associated with each of the sequence switches 100 are designated 101 to 103 inclusive; those associated with each of the sequence switches 200 are designated 201 to 224 inclusive; those associated with each of the sequence switches 300 are designated 301 to 304 inclusive; and those associated with each of the sequence switches 400 are designated 401 to 413 inclusive.

30 To each of the contacts associated with the various sequence switch cams are applied certain numerals. These numerals in the case of the cams 101, 201, 301 and 401 indicate the only positions of the associated sequence switch in which these particular contacts are open; the numerals applied to all of the other contacts of each sequence switch indicate the only positions of the particular associated switch in which the associated contacts are closed.

35 The sequence switches 100 merely act as timing switches and have only one resting position. The resting positions of the other sequence switches, and the stages of operation with which these positions are associated, are as follows:

40

Sequence switch 200.

1. Normal.
2. Awaiting starting circuit.
3. Awaiting starting circuit release.
4. Hunting calling line.
5. Awaiting preceding finder circuit.
6. Awaiting operator's selecting circuit.
7. Releasing operator's selecting circuit.
8. Hunting cord circuit.
9. Talking.
10. Line finder at tell-tale.
11. Cord selector at tell-tale.
12. Line finder return.
13. Cord selector return.

Sequence switch 300.

1. Awaiting a call.
2. Position vacant.
3. Position busy.

Sequence switch 400.

1. Normal.
2. Listening in.
3. Listening out.

The manner in which the system is organized will appear from the description of its operation which follows. It will be assumed that the subscriber at station A initiates a call. When the telephone receiver is taken from the switchhook, a circuit is closed that extends by way of both windings of the line relay 12 and both limbs of the telephone line, and is completed in the contacts of the switchhook at the subscriber's station. The flow of current in this circuit energizes the line relay 12, which in operating applies at its right-hand armature and contact, a ground to the conductor 18. This causes current to flow from battery through the winding of the relay 19, sequence switch contact 103 (18 $\frac{3}{4}$ to 1 $\frac{1}{4}$), conductor 18 and ground at the contacts of the operated line relay 12. The relay 19 attracts its armature and closes a circuit that extends from battery through the right-hand winding of the associated relay 24, front contact of relay 19, back contact of relay 22 and lower armature and back contact of relay 23 to ground. Relay 24 operates and closes in its left-hand front contact a circuit that extends from battery by way of the winding of the associated group trip magnet 16 and the left-hand winding of the relay 24, in parallel, to the front contact of that relay, and thence by way of conductor 58, the winding of the relay 22, and the lower armature and back contact of the relay 23 to ground.

Current flowing in the circuit traced above operates the trip magnet 16 of the group in which the calling line is located, locks up the relay 24 of the associated group and operates the relay 22 common to all of the groups. The trip magnet 16 rotates its associated trip rod to bring all of the yokes into position to trip the corresponding set of brushes of whichever of the line finder switches is started. The group relay 24 breaks, in its left-hand back contact, the circuit of the conductor 58 to the corresponding relays 24 of the succeeding groups of the series.

The relay 24, in its right-hand front contact, also completes a circuit that extends from battery through the motor magnet of the sequence switch 100, and contact 102 (18 $\frac{3}{4}$ to 1 $\frac{1}{4}$) of that switch. In moving out of position 1, sequence switch 100 closes its contact 101 and opens its contact 103 after leaving position 1 $\frac{1}{4}$. As contact 101 is closed in all positions excepting position 1 of the

sequence switch, the switch is caused to make one complete rotation; and as contact 103 of the sequence switch is open in all positions excepting positions 18 $\frac{1}{4}$ to 1 $\frac{1}{4}$, the conductor 18 is held open while the sequence switch is making its revolution and until it gets back to position 1. The time required by the sequence switch to make one complete rotation is so regulated as to be greater than that occupied by the line finder switch in finding the terminals of any calling line. The action, therefore, is such as to interrupt the group conductor 18, and hold it open until after the line relay 12 of the calling line has been released as a result of the finding of that line.

The relay 22, common to all the groups, in operating opens in its back contact the circuit of the conductor 57, which extends serially through the back contacts of the relays 19 of the various groups. As this conductor 57 is the path over which the relay 19 of any group serves to effect the initial energization of the associated relay 24 and the operation of the corresponding trip magnet, the interruption of this conductor insures the operation of only one trip magnet and the tripping of only one set of brushes on a started line finder switch.

30 The common relay 22, when it operates, applies ground to the starting conductor 29 to start a finder switch hunting for the calling line. The starting conductor 29 has branches extending to like sequence switch 35 cams 206 of all of the finder circuits terminating upon the line finders that have access to the calling line. But, for reasons which will hereinafter be explained, the sequence switch 200 of only one of these 40 finder circuits is standing in its 2 position. Assuming that this is the sequence switch of finder circuit F, when the relay 22 is actuated by the calling line, as already described, a circuit is completed that extends 45 from battery through the left-hand winding of relay 30, sequence switch contacts 206 (2), conductor 29, front contact and armature of starting relay 22, lower armature and back contact of relay 23 to ground. The 50 right-hand winding of relay 30 is at this time also included in parallel with the left-hand winding of the relay in the energizing circuit, the parallel branch being from battery through resistance coil 56, sequence 55 switch contact 217 (2 to 9) right-hand winding of relay 30, sequence switch contacts 220 (2) and (1 to 13), thereafter joining the conductor that extends from the left-hand winding of relay 30, and to ground 60 over the circuit already traced. The effect of this is to give the relay 30 the benefit of the energizing action of both windings.

As a result of the closure of the circuit traced above, the relay 30 is energized and 65 closes a circuit that causes the associated

sequence switch 200 to move out of position 2. This circuit extends from battery through the motor magnet of the sequence switch 200, sequence switch contact 202 (2), right-hand front contact and armature of relay 30, sequence switch contact 208 (2 to 7), conductor 79, commutator segment M of the associated cord finder switch CS, and to ground by way of the brush that is in engagement with this commutator segment. Relay 30, in attracting its armatures, also closes a locking circuit for itself that extends from battery by way of the resistance coil 56, sequence switch contacts 217 (2 to 9), the right-hand winding of the relay 30, sequence switch contacts 216 (2 to 4) and (2 to 9), front contact and left-hand armature of the relay 30, and armature and back contact of the relay 37 to ground.

As a result of the closure of its motor magnet circuit in the right-hand front contact of the relay 30, the sequence switch 200 moves out of position 2 and comes to rest in position 3. In position 3 of the switch, a circuit is closed that extends from battery by way of the up-drive magnet 32 of the corresponding line finder switch LF, conductor 59, sequence switch contact 207 (3 to 4), front contact and right-hand armature of relay 30, sequence switch contact 208 (2 to 7), and to ground by way of conductor 79 and the commutator segment M and associated brush of the corresponding cord finder CS. The energization of the up-drive magnet 32 starts the upward movement of the corresponding elevator rod with its associated sets of brushes. At the outset of the upward movement of the elevator rod, all of the brush trip levers are moved past the corresponding trip yokes. The only trip magnet that is energized in this case is the magnet 16 which corresponds with the group in which the calling line is located; and, consequently, the only trip yoke in position to engage a trip lever on the elevator rod is the one which controls the brushes 40, 41, 42 and 43 that are adapted to engage the terminals of that particular group of lines. This set of brushes, therefore, is released and made operative and the other sets are held clear of their associated line terminals.

As soon as the set of brushes corresponding with the calling line is tripped, the group apparatus, by means of which the lines control the brush tripping and line finder starting operations, may be returned to its normal condition. The first step in this restoring operation is effected by the closure of a circuit which is completed by way of the K segment of the line finder commutator immediately after the brushes are tripped. This circuit extends from battery in parallel branches through the relays 23 and 33 (see Fig. 1), conductor 26, 130

sequence switch contact 209 (2₄ to 3), conductor 68, and to ground by way of the K segment of the line finder commutator and its associated brush. The energization of the relay 23 interrupts, at the lower back contact of that relay, the previously described circuit that has up to this time maintained the energization of the trip magnet 16, the group relay 24 and the common 10 starting relay 22. Relay 23, at its upper front contact, closes a locking circuit for itself and the associated relay 33 that extends by way of conductor 25 and the sequence switch contacts 210 (2₄ to 1) of all 15 of the finder circuits in series, to ground at a point beyond the last switch of the series.

As has already been stated, normally there is only one of the finder circuits with 20 its sequence switch in position 2 awaiting the receipt of a call. When the call comes in, this sequence switch is immediately moved to position 3, in the manner described above. Therefore, at this stage of the 25 operation, the sequence switches of all of the finder circuits are in position to close their contacts 210. The locking circuit for the relays 23 and 33 is, therefore, held closed until another one of the finder circuits has 30 its sequence switch moved into position 2. This is accomplished by relay 33, which, in operating, applies a ground to conductor 28 to move the sequence switch of another finder circuit out of position 1 and into position 2, and which also applies a ground to the conductor 27 to move the sequence switch of the appropriated finder circuit out of position 3.

Assuming that the sequence switch of 40 finder circuit F' is in position 1 and that the sequence switch of finder circuit F² is in some position between 4 and 17, that finder circuit being assumed to be in use, the operation of the relay 33 completes the following circuit: from battery, through the motor magnet and contacts 203 (1) of the sequence switch of finder circuit F', contacts 211 (1) of the same sequence switch, contacts 211 (3 to 17) and (4 to 17) of the sequence switch 45 200 of finder circuit F², contacts 211 (3 to 17) and (3 to 3₄) of the sequence switch 200 of finder circuit F, conductor 28, lower contact and armature of the relay 33 to ground. This causes the sequence switch of finder circuit F' to move into position 2.

If by any chance the sequence switch of 50 finder circuit F' should fail to be moved into the call-awaiting position 2 when the relay 33 operates, it will be moved into that position when the sequence switch of the appropriated finder circuit F moves into position 5 at a slightly later stage in the operation. The circuit by which this result would, under the circumstances, be accomplished extends 55 from battery through the motor magnet and

contact 203 (1) of the sequence switch of finder circuit F', contacts 211 (1) of that sequence switch, sequence switch contacts 211 (4 to 17) and (3 to 17) of finder circuit F² (assumed to be in use), and thence 70 by way of contacts 222 (5 to 1) of all of the finder circuit sequence switches in series to ground. In other words, at any time that the finder circuit sequence switches are all standing in position 1 or in position 5 and 75 beyond, a ground is applied by way of the 222 cams in series that moves one of the switches into position 2, and thus places the associated finder circuit in its call-awaiting condition. The sequence switch of finder 80 circuit F is moved out of position 3 by the closure of a circuit that extends from battery through the motor magnet and contacts 203 (3) of the sequence switch of that circuit, conductor 27 and upper contact and armature of relay 33 to ground. As soon as the sequence switch of finder circuit F' moves into position 2, it opens at its contacts 210 the circuit by way of conductor 25 which has been maintaining relays 23 and 33 energized, 90 and these relays release their armatures. Relay 23, in releasing, reconnects to ground the circuit which extends in branches 57 and 58 through its various sets of group relays, thus again giving the groups access to the 95 starting circuit.

At this stage of the operation of the system, the sequence switch of the appropriated finder circuit F is in position 4, and the elevator rod of the associated line-finder LF 100 is moving up with the set of brushes tripped that corresponds with the group in which the calling line is located. As the tripped brushes rise, they come into engagement successively with the sets of contacts corresponding with the different lines of the group. At the instant of engagement of the brush 43 with the terminal 47 of each line, the test relay 37 of the finder circuit is connected with local conductor 253 of that line. 110 This local conductor has two branches, one or the other of which is closed depending upon the condition of the line relay 12 of the associated line. If the line relay is inert, as it is when the line is not calling, or when 115 the line has been connected with and its cut-off relay operated, the local conductor 253 of the line is connected with ground by way of an identifying device 252 and a relatively low potential battery. If the line relay 12 is energized, as it is when the line is calling and is not connected with, the local conductor 253 of the line is connected with ground by way of the right-hand back contact and armature of the protective relay 250 common 125 to a group of lines, the energizing winding of this relay, and a relatively high potential battery 251. Therefore, as the elevator rises and the brush 43 engages the corresponding terminal 47 of each of the lines of the group 130

in which the calling line is located, a circuit is completed as each line terminal is engaged that extends, either by way of the low potential battery, the device 252, and the left-hand back contact and armature of relay 12 to the local conductor 253 of the line; or by way of the high potential battery, the winding of common relay 250, the right-hand armature and back contact of that relay, and 5 the left-hand front contact and armature of relay 12 to the local conductor 253; and thence by way of line terminal 47, brush 43, conductor 51, finder sequence switch contacts 224 (1 to 8) and (2 $\frac{1}{4}$ to 4), and winding of 10 relay 37 to ground.

The relay 37 is so adjusted that it will respond only to the current flow produced in the circuit of the high potential battery, and not to that produced by the low potential 15 battery. As the line relay 12 of the calling line is energized, thus connecting the high potential battery to the associated local conductor 253, the test relay 37 responds when the brush 43 engages the terminal 47 of the calling line. The response of the relay 37 causes that relay to interrupt in its back contact the previously traced circuit by way of the left-hand armature and front contact of the relay 30, sequence switch contacts 216, 20 and right-hand winding of relay 30, which circuit had been holding the relay 30 locked up from the moment that the relay was first energized upon the receipt of the call. Relay 30 in releasing its armatures breaks its own 25 locking circuit, and also breaks the previously-traced path, including sequence switch contacts 208, right-hand armature and front contact of the relay 30, and sequence switch contact 207, over which current has been 30 flowing to energize the up-drive magnet 32 of the line finder. Therefore, the operation of the relay 37 upon the finding of the calling line acts to effect the instant deenergization of the up-drive magnet 32, and thus to 35 stop the brushes upon the terminals of the calling line.

In order that the brushes may always be stopped in registration with the line terminals, the locking circuit of the relay 30 has 40 an alternative path to ground by way of sequence switch contact 215 (2 to 4), conductor 66, the C segment of the line finder commutator and the corresponding brush to ground. The C segment of the commutator is so formed and related to its brush that the connection between the two is interrupted only when the corresponding line brushes on the elevator rod are in engagement with corresponding sets of line terminals. The unlocking of the relay 30, and 45 the consequent stopping of the upward movement of the elevator rod, can therefore occur only when the line brushes are in proper relation to the terminals of the 50 calling line.

When the relay 30 is deenergized, as a result of finding the calling line, it also completes a circuit that extends from battery through the motor magnet and contact 202 (3 to 4) of the finder sequence switch, right-hand back contact and armature of the relay 30, sequence switch contact 208 (2 to 7), conductor 79, and M segment and corresponding brush of the cord selector CS to ground. The closure of this circuit moves 75 the sequence switch out of position 4.

When the finder sequence switch reaches position 4 $\frac{1}{4}$, it closes a path for the flow of current through the cut-off relay 11 of the calling line by way of resistance coil 64, sequence switch contact 212 (4 $\frac{1}{4}$ to 12 $\frac{1}{2}$), conductor 50, brush 42, line terminal 46 and conductor 53. The flow of current in this circuit operates the cut-off relay 11 to disconnect the relay 12 from the circuit, and that relay in releasing its armatures disconnects the high potential test battery from the local conductor 253 and disconnects ground from the common conductor 18. The disconnection of ground from conductor 18 occurs before the timing sequence switch 100 has completed its cycle of rotation and reconnected conductor 18 with relay 19.

The brushes of the line finder switch are now at rest in engagement with the terminals of the calling line, the sequence switch 200 of finder circuit F is at position 6, the group starting circuit represented by the conductors 57 and 58 and the associated relays 22, 23 and 33 has been released and is in readiness to respond to another calling line, and the sequence switch of another finder circuit has been moved into position 2, and thus brought into operative relation 105 with the starting conductor 29.

When the sequence switch of the finder circuit over which the call is being extended has reached position 6, the finder circuit is brought into operative relation with the operators' selecting circuit. When the finder sequence switch reaches position 6, it awaits the closing of a circuit, the completion of which is dependent upon the condition of the other finder circuits of the associated group. This circuit extends from battery through the left-hand winding of the relay 30, contact 219 (6) of the appropriated circuit sequence switch, contacts 219 (9 to 4) of the sequence switches of the 115 associated finder circuits preceding it in the series, conductor 76, outer armature and back contact of relay 54, and right-hand back contact and armature of relay 61 to ground. A branch path for the energization of relay 30 also exists at this time, this branch path extending from battery through resistance 56, sequence switch contacts 217 (2 to 9), right-hand winding of relay 30, sequence switch contacts 220 (6) and (1 to 120 130

- 13), and contact 219 (6) of the appropriated finder circuit sequence switch, from which point it extends to ground at the right-hand back contact and armature of 5 the relay 61 over the path already traced. This circuit for the energization of relay 30 is open either in the cam 219 of a preceding finder sequence switch in the series, or in contacts of the relay 54 or 61 as long as 10 any sequence switch of the series is in positions 4 to 9. That is, it is open from the time the line finder switch of any associated finder circuit finds a calling line until the cord finder switch of that circuit has 15 moved far enough to trip the brushes corresponding with the selected operators' position, as will be described. Not until this has occurred will the above traced circuit of the awaiting finder circuit be closed. 20 When the circuit is closed, the relay 30 attracts its armatures and completes a circuit that extends from battery through the motor magnet and sequence switch contact 202 (6 to 7) of the sequence switch 200, right- 25 hand front contact and armature of relay 30, sequence switch contact 208 (2 to 7), conductor 79, and segment M and corresponding brush of the cord selector commutator to ground. The completion of this 30 circuit moves finder sequence switch out of position 6.
- When the sequence switch 200 reaches position 6 $\frac{3}{4}$, it closes a circuit that extends from battery by way of the winding of relay 55 35 (Fig. 3), conductor 71, sequence switch contact 218 (6 $\frac{3}{4}$ to 8), conductor 67, and segment M and corresponding brush of the line finder commutator to ground. The operation of the relay 55 applies ground to the conductors 40 81 extending to all of the operators' positions. At each of the positions where the operator is at her station and is in readiness to receive a call, the associated relay 91 (Fig. 4) is inert, and the operator's telephone se- 45 quence switch 300 is in its 1 position. Con-sequently at each of such positions, a circuit is closed that extends from battery, through the winding of the associated relay 92, left- hand armature and back contact of relay 91, 50 sequence switch contact 304 (1), conductor 81, armature and front contact of relay 55 to ground. The relay 92 of each awaiting position therefore attracts its armatures and closes a circuit that extends from battery, 55 through the front contact and armature of the relay 92 to the conductor 82, and thence to ground by way of the windings of the relays 77 corresponding to that operator's position at the various cord selector frames. 60 When the finder sequence switch 200 reaches position 7, in which position it comes to rest, it closes a circuit that extends from battery through the winding of relay 54, left- hand back contact and armature of relay 61, 65 conductor 73, finder sequence switch contact 218 (7 to 8), conductor 67, and segment M and corresponding brush of the line finder commutator to ground. Relay 54 attracts its armatures and completes a branch of the circuit traced above, which branch extends 70 from conductor 73 by way of the armature and back contact of the relay 63, front contact and inner armature of relay 54, right- hand armature and back contact of relay 52, 75 armature and front contact of relay 77 (which relay is energized, as previously de- scribed, as a result of the corresponding operator's position being in readiness to receive a call), right-hand back contact and switch spring of relay 93 of the corresponding 80 group, winding of associated relay 94, wind- ing of relay 93, left-hand switch spring and resting contact of relay 93, conductor 83, left-hand back contact and armature of relay 95 at the O operator's position to 85 battery. Upon the closure of the above- traced branch circuit, group relays 93 and 94 are energized in parallel with the relay 54. Relay 93 in operating discon- nects its own energizing winding and that of 90 relay 94 from the previously traced path to battery by way of the left-hand back contact and armature of relay 95, and connects them in a path which extends to battery by way of conductor 84 and the winding of the 95 relay 95. This causes the relay 95 also to be energized and to interrupt in its left-hand armature and back contact the path by way of conductor 83 over which the relays 93 and 94 were initially energized. 100
- Relay 94 in operating closes a circuit from battery through the winding of the trip magnet 20 corresponding to the selected operator's position, and to ground by way of the right-hand armature and front contact 105 of the relay 94. This relay also closes a cir- cuit that extends from battery through the winding of the relay 63 and the left-hand ar- mature and front contact of the relay 94 to ground. The relay 63 in operating closes a 110 branch that extends from the conductor 73 (grounded by way of contact 218 (7 to 8) of the line finder sequence switch) through the armature and front contact of relay 63, back contact and armature of relay 254, con- 115 ductor 72, sequence switch contacts 220 (7) and (1 to 13), and left-hand winding of relay 30 to battery. A branch energizing path for relay 30 also extends from conductor 72 by way of sequence switch contacts 220 (7), 120 right-hand winding of relay 30, sequence switch contacts 217 (2 to 9), and resistance 56 to battery. Relay 30 attracts its ar- matures and closes a circuit that extends from battery through the motor magnet and se- 125 quence switch contact 202 (6 to 7), front contact and right-hand armature of relay 30, sequence switch contact 208 (2 to 7), con- ductor 79, and segment M and corresponding brush of the cord selector commutator to 130

ground. The closure of this circuit moves sequence switch 200 out of position 7. Furthermore, relay 30 in operating is locked up over a circuit that extends from battery 5 through resistance 56, sequence switch contacts 217 (2 to 9), right-hand winding of relay 30, sequence switch contacts 216 (7 to 9) and (2 to 9), front contact and left-hand armature of relay 30 and armature and back contact 10 tact of relay 37 to ground.

When the sequence switch reaches position 8 it closes a circuit that starts the upward movement of the brush-carrying rod of the cord selector switch, this circuit extending from battery through the up-drive magnet 34 of the cord finder, conductor 89, sequence switch contact 207 (8 to 9), right-hand front contact and armature of relay 30, sequence switch contact 218 (8 to 9), conductor 67, commutator segment M of the line finder and corresponding brush to ground.

In order to prevent the upward movement of the cord selector switch from being started before the selection of a particular 25 one of the trip magnets 21, 22 has been definitely effected, the circuit of conductor 72, over which the relay 30 is energized when relay 63 operates, is placed under the control of a slow releasing relay 254. The energizing winding of the slow releasing relay 254 is in parallel with the energizing winding of the relay 54, and the relay 254 is consequently energized by way of conductor 73 and cam 218 of the finder sequence switch 30 when the sequence switch reaches position 7. The energizing path of the relay 254 is by way of the back contact and armature of relay 63, and the armature and back contact of relay 254 controls the path to relay 30 by 40 way of the conductor 72, holding this path open as long as the relay 254 is energized. When therefore the actuation of one of the relays 94 operates the relay 63, the operation of the relay 63 does not instantly close conductor 72 to energize relay 30 and move the finder sequence switch to position 8 where the upward movement of the cord selector brushes is started. Instead, the closure of this energizing path for relay 30 is delayed 45 until the relay 254 has had time to deenergize, after the interruption of its circuit at the back contact of relay 63, and release its armature to close the path of conductor 72. Under certain special circumstances in the 50 operation of the operator's selecting apparatus it is possible for the trip magnets associated with two operators' positions on the same cord selector frame, or for two trip magnets associated with same operator's position upon two different frames, to be momentarily operated. By providing the slow-acting relay 254 for delaying the advance of the finder sequence switch to its next stage, the possibility of one finder circuit selecting

two operators' positions, or of two finder 65 circuits on different frames selecting the same operator's position, is prevented.

At the outset of the upward movement of the cord finder brush rod, the tripping levers of the various sets of brushes are 70 brought simultaneously into operative position with respect to the corresponding tripping yokes, and that set of brushes is tripped and made operative whose trip magnet is at the time energized. In the present instance, 75 it is assumed that this is the trip magnet 20 associated with the terminals of the group of connecting cord circuits extending to the O operator position.

Immediately after the set of brushes is 80 tripped, the common operators' selecting circuit is restored so as to be available for the use of other cord finder switches. This is effected through the medium of a circuit that is completed by the grounding of the K segment 85 of the cord finder commutator, this segment being so located as to be engaged by its brush immediately after the tripping levers of the sets of brushes pass the associated tripping yokes. The circuit referred to extends from battery through the winding of relay 61, conductor 74, sequence switch contact 221 (7₄ to 8), conductor 80, cord finder commutator segment K and its corresponding brush to ground. Relay 61 in operating 90 opens, at its left-hand back contact, the previously-traced circuit by way of conductor 73 which, up to this time, has been holding energized the relay 95 at the O operator's position and the relays 93 and 94 corresponding 95 to this position on the cord finder frame. The release of the relay 94 deenergizes the corresponding trip magnet 22 and the common relay 63. The deenergization of the relay 93 reestablishes, subject to the release 100 of relay 61, the control of other finder circuits over the brush tripping mechanism of the associated cord finder frame.

Relay 61, in operating, closes a locking circuit for itself by way of conductor 73, sequence switch contact 218 (7 to 8), conductor 67, commutator segment M of the line finder and corresponding brush to ground. It also completes a circuit that extends from battery through the motor magnet and contact 204 (8) of the sequence switch 200, conductor 75, right-hand front contact and armature of relay 61 to ground. The closure of this circuit moves sequence switch 200 out of position 8. In moving out of position 8, 110 the sequence switch opens its contacts 218 (7 to 8), thus deenergizing relay 61 and again extending conductor 73 to the relay 54 and the conductors over which the operator's selection is effected. In closing its 115 right-hand back contact upon release, relay 61 also restores the continuity of conductor 76 and makes it available for moving out of

position 6 the sequence switch of some other finder circuit which may be waiting for access to the operator's selecting circuit.

After the cord selector switch CS passes 5 the brush-tripping position, it continues its upward movement until the brushes are stopped by engaging the terminals of one of the connecting circuits that is not in use. The idle or busy condition of the connecting 10 circuit is indicated by the presence or absence of high-potential battery on the test terminal 118 of each connecting circuit. When the brushes engage the terminals of an idle connecting circuit, a path for the 15 flow of current is completed from high potential battery 251 (see Fig. 4), through the winding of common protective relay 258, armature and back contact of that relay, lower back contact and armature of relay 20 259, conductor 128, armature and back contact of relay 420, contact 406 (1) of the listening key sequence switch, conductor 88, test terminal 118 and brush 114 of the cord selector, conductor 99, finder sequence switch 25 contacts 206 (8 to 9) and the winding of relay 37 to ground. Relay 37 thereupon attracts its armature and opens the previously traced locking circuit that has been holding relay 30 energized. Relay 30, in releasing 30 its armatures, opens at its right-hand front contact and armature the energizing circuit for the up-drive magnet 34, thus stopping the brushes of the cord selector switch in engagement with the terminals of the selected 35 connecting circuit. In engaging its back contact, the right-hand armature of relay 30 closes an energizing circuit for the motor magnet of the finder sequence switch which extends by way of cam 202 (8 to 9), 40 back contact and right-hand armature of relay 30, cam 218 (8 to 9), conductor 67, and the M segment and corresponding brush of the line-finder commutator to ground. The closure of this circuit moves sequence switch 45 200 out of position 9, whereupon the switch continues to move until it reaches position 14, where the talking circuit is completed at cams 213 and 214.

An instant after the finder sequence switch 50 leaves position 9, it closes a circuit that extends from battery through the windings of relays 421 and 423 (see Fig. 4) in parallel, listening key sequence switch contacts 407 (1), left-hand back contact and armature of relay 422, conductor 87, cord selector switch terminal 117 and corresponding brush 113, conductor 98, and finder sequence switch contacts 217 (9 $\frac{1}{4}$ to 14) and (9 $\frac{3}{4}$ to 11) to ground. Relay 421 in operating closes a 55 locking circuit for itself and relay 423 that extends by way of its upper front contact and armature, and sequence switch contact 405 (1 to 6) to ground. Relay 421 also closes a circuit that extends from battery

through the motor magnet and cam 403 (1) 65 of the listening key sequence switch and lower front contact and armature of relay 421 to ground. The closure of this circuit causes the listening key sequence switch to move out of position 1, and, in doing so, to 70 open the test conductor 88 at sequence switch contact 406 (1), and also to open at sequence switch contact 407 (1) the path over which the relays 421 and 423 were first energized.

Relay 423, associated with relay 421, in 75 operating closes a circuit that extends from battery through the winding of relay 422 and upper front contact and armature of relay 423 to ground. As a result relay 422, prior to the moving of the listening key sequence 80 switch out of position 1, has disconnected conductor 87 from connection with battery by way of sequence switch contact 407 (1) and the windings of relays 421 and 423, and has connected it with an alternative path to 85 battery by way of the left-hand front contact of relay 422 and resistance device 424.

When the listening key sequence switch reaches position 2, an additional path to 90 ground for holding the relay 422 energized, is closed by way of sequence switch contact 412 (2 to 7).

The energization of relay 423 at the instant the cord is seized also brings about the closure of a circuit that extends from 95 battery through the winding of the common relay 259, conductor 129, and lower front contact and armature of relay 423 to ground. Relay 259 in operating opens at its lower armature and back contact the circuit over 100 which the potential of the high voltage test battery 251 is supplied to the test conductors 128 of all of the connecting cords of the position. Thus the electrical condition which permits a connecting cord to be seized by a 105 cord selector is withdrawn from the selected cord and also from its associated cords at the instant of seizure, and is not reapplied to such of the cords as may be in condition to be selected until the common 110 relay 259 is deenergized. The deenergization of relay 259 occurs when the relays 421 and 423 are released by the opening of their locking circuit at cam 405 when the listening key sequence switch moves beyond position 6.

When the listening key sequence switch 400 is moved out of position 1, in the manner described above, it continues its movements until it reaches position 7. In position 7 the 120 cams 408, 409, 410 and 411 of the listening key sequence switch interrupt the talking strands of the connecting circuit and include between their severed ends a loop that has connection by way of conductors 135 and 125 136 with the operator's telephone set 147. This puts the operator in communication with the calling subscriber. At the same

time the operator is informed of the identity of the connecting cord over which the call is being extended by the flashing of the lamp 161 associated with that cord, the circuit for illuminating this lamp extending from battery through the outer back contact and armature of relay 500, lamp 161, sequence switch contact 413 (7), and interrupter 162 to ground.

- 10 At this particular time the operator's sequence switch 300 is in position 17, or moving to that position. When the position was selected the operator's sequence switch was standing in position 1 and the relay 91 was inert, thus providing a path for the energization of the relay 92, the operation of which relay when an operator's position is to be selected serving to mark that particular position as being unengaged or selectable. When the position is selected, the relay 95 is operated in the manner previously described. In operating, the relay 95 closes a circuit that extends from battery through the motor magnet and cam 302 (1) of the operator's sequence switch, right-hand front contact and armature of relay 95, and right-hand front contact and armature of relay 125 to ground. The relay 125 at this time is operated, as its energizing path is completed by way of local contacts 127 of the operator's telephone jack 126, which contacts are closed when the operator is at her position and has her telephone plug inserted in the telephone jack. As a result of the closure of the circuit traced above, the operator's sequence switch 300 is moved out of position 1, thus opening the energizing path of relay 92 in sequence switch contact 303 (1) and making the position unselectable.
- 20 The next resting position of the operator's telephone sequence switch 300 is position 4; but as relay 125 is energized, the motor magnet has an energizing circuit in this position by way of sequence switch contact 302 (4) and the left-hand front contact and armature of relay 125 to ground, and consequently the sequence switch moves on to its next resting position 17. The sequence switch remains in position 17, keeping the operator position unselectable, until at a later stage in the operation the switch 192 is operated in any suitable manner to close its contacts. At this time a circuit is closed that extends from battery through the motor magnet and cam 302 (17) of the operator's telephone sequence switch and closed contacts of switch 192 to ground. The closure of this circuit permits the sequence switch to move from position 17 to position 1, thus rendering the operator's position again available for receiving calls.

25 The operator's position is also rendered unselectable when the operator's telephone set is connected with one of the connecting circuits. This is effected through the me-

dium of the relay 91. When the listening key sequence switch 400 of any of the connecting circuits of the operator's position is moved to position 7 to bring the operator's telephone set into connection with the corresponding circuit, an energizing path is completed that extends from battery through the winding of relay 91, conductor 137, and listening key switch contact 404 (2 to 9) to ground. The completion of this circuit causes the relay 91 to attract its armature and interrupt the path over which the relay 92 is adapted to be energized, thus preventing the operation of the associated selection controlling relays 77.

30 The removal of the telephone plug from the operator's telephone jack 126 when the operator leaves her position, also renders the position unselectable. When the plug is removed, the breaking of the circuit at the local contact 127 causes relay 125 to become inert and release its armatures. This closes a circuit that extends from battery through the motor magnet and cam 302 (1) of the operator's telephone sequence switch, and to ground by way of the left-hand back contact and armature of relay 125. In moving out of position 1 as the result of the closure of this circuit, the sequence switch interrupts the energizing path for the relay 92 in sequence switch contact 303 (1), thus preventing the operation of the corresponding selection controlling relays 77 when a connection is to be extended.

35 Reference has heretofore been made to the operation of the common relay 259 which is energized to remove the test condition from the selected connecting cord and all of its associated connecting cords at the instant the cord is seized. This relay when it operates, also acts to complete a circuit that extends from battery through the winding of relay 91 and the winding of relay 193 in parallel, and thence to ground by way of the upper front contact and armature of relay 259. Relay 193 in operating, closes a circuit from battery through the motor magnet and contact 304 (1) of the operator's telephone sequence switch, and front contact and armature of relay 193 to ground. The closure of this circuit safeguards the operator's telephone sequence switch from standing or stopping in position 1 from the instant the cord circuit is seized. Relay 91 in operating insures the inaccessibility of the operator's position at this time by opening the path over which relay 92 must be energized.

40 When the operator has been put into communication with the calling subscriber by the movement of listening key sequence switch 400 to position 7, as already described, and when the operator has learned the number of the line that is wanted, the connection may be completed by inserting 130

calling plug 425, in which, in the present instance, the connecting circuit is represented as terminating, into the spring jack 14² of the called subscriber's line. Instead of 5 a plug and spring jack, any other of the well-known switching devices or mechanisms for establishing connection between a connecting circuit and a telephone line may obviously be employed. In the present instance, 10 the connection-extending means is represented as a cord circuit provided with a repeating coil 426, answering and calling supervisory relays 427 and 428, respectively, and a switch 429 for applying ringing current from the source 430 to ring the bell at the called subscriber's station D. As all of 15 these parts may have their usual functions and may operate in the usual way, a description of them and of the exact manner in 20 which the cord circuit is organized is thought to be unnecessary.

When the calling plug 425 is inserted in the called line spring jack, an energizing circuit is completed that includes serially 25 the windings of the connecting cord relays 420 and 431 and the cut-off relay 11² of the called line. The cut-off relay 11² may have its usual function of disconnecting the line relay 12², thus depriving the line of control 30 over the calling apparatus. The relay 420 in operating interrupts at another point the path of the test conductor 88, thus keeping the cord circuit unselectable while the plug 425 is in the spring jack of the called line. 35 The relay 431 at its left-hand back contact breaks the connection of the tip of the plug with the conductor 133, which may extend to the test winding of the operator's telephone set, and at its left-hand front contact 40 closes the tip strand of the connecting cord to complete the talking circuit. The relay 431 in operating also closes a circuit that extends from battery through the winding of the relay 500 and the right-hand front contact and armature of relay 431 to ground. The relay 500 at its outer armature and back 45 contact interrupts the circuit of the flashing call lamp 161 and extinguishes the lamp. At its inner armature and front contact, the relay 500 closes a locking circuit for the holding relay 422 that extends by way of the right-hand front contact and armature of that relay. The relay 500 also closes a circuit that extends from battery through the 50 motor magnet and contact 402 (7) of the listening key sequence switch, outer left-hand front contact and armature of relay 500, and right-hand back contact and armature of relay 421 to ground, the relays 421 55 and 423 having been released by the opening of their locking circuit at cam 405 when the listening key sequence switch moved beyond position 6. The listening key sequence switch moves out of listening-in position 60 65 as a result of the closure of this last men-

tioned circuit, and comes to rest in position 15.

The termination of the conversation between the subscribers is indicated in the usual way by signals displayed when the supervisory relays 427 and 428 become inert, and disconnection is effected by withdrawing the calling plug 425 from the spring jack 14². The withdrawal of the calling plug 425 interrupts the energizing circuit of the relays 431 and 420, and these relays release their armatures. The relay 431 in releasing breaks the energizing circuit of the relay 500, and that relay in releasing closes a circuit that extends from battery through the motor magnet and cam 402 (15) of the listening key sequence switch outer left-hand back contact and armature of relay 500, and lower back contact and armature of relay 421 to ground. The listening key sequence switch thereupon moves out of position 15, and comes to rest in position 1. Relay 500 in releasing also opens at its inner left-hand front contact and armature, the locking circuit of the holding relay 422, and that relay, 90 in releasing, breaks the connection of conductor 87 with battery by way of the device 424. When current ceases to flow through conductor 87, the relay 30 of the finder circuit, which has been included in the path of current flow by way of conductors 87, 98, 50 and 53, and the finder sequence switch cams 217 and 212, releases its armatures. This closes the circuit from battery through motor magnet and cam 202 (14) of the finder sequence switch, left-hand back contact and armature of relay 30, and armature and back contact of relay 37 to ground. This moves the finder sequence switch out of the talking position 14. 105

When the finder sequence switch reaches position 15 a circuit is closed for the energization of the relay 30 that includes in parallel branches both windings of that relay. One branch of this circuit extends from battery through resistance 56, sequence switch contacts 217 (15 to 16) and (12 to 16) right-hand winding of relay 30, sequence switch contacts 220 (15) and (11 to 16) to conductor 67; the other branch extends from battery, 110 through the left-hand winding of relay 30, and sequence switch contacts 220 (15) and (11 to 16) to conductor 67 thence both branches extend by way of conductor 67, and M segment and corresponding brush of the line-finder commutator to ground. Relay 30 in operating closes a branch path to ground for maintaining its energization, this path extending from the right-hand winding of relay 30, by way of sequence switch contacts 216 (15 to 16), left-hand front contact and armature of relay 30, and armature and back contact of relay 37 to ground. Relay 30 in operating also closes a circuit that extends from battery, through motor magnet 115 120 125 130 135

and contact 202 (15) of the finder sequence switch, right-hand front contact and armature of relay 30, sequence switch contact 218 (15), conductor 67, and M segment and corresponding brush of the line-finder commutator to ground. The completion of this circuit energizes the finder sequence switch 200 and causes it to move its cams to position 16.

In moving out of position 15 the sequence switch opens at its 220 cam, the branch of the energizing path that includes the left-hand winding of relay 30, and also opens the path to ground by way of conductor 67 and the M segment of the line-finder commutator; the energization of the relay being maintained in position 16 of the sequence switch by way of the branch that includes its right-hand winding, cam 216, left-hand contacts of relay 30, and resting contacts of relay 37. This circuit is held closed and relay 30 is kept energized until the cord circuit through which the call was extended has returned to its normal condition. When this occurs a circuit is closed that extends from high-potential battery 251, through the winding and contacts of common relay 258 (see Fig. 4), armature and back contact of relay 259, conductor 128, armature and back contact of relay 420, sequence switch contacts 406 (1), closed when the cord circuit returns to normal, conductor 88, cord selector contact 118 and corresponding brush 114, conductor 99, sequence switch contact 208 (16), right-hand armature and front contact of relay 30, sequence switch contacts 224 (9 to 17) and (16), and winding of relay 37 to ground. The closure of this circuit energizes relay 37, which attracts its armature and opens the previously-traced holding circuit of the relay 30. Relay 30 in releasing its armatures closes a circuit that extends from battery through the winding of down-drive magnet 62 of the line-finder switch, conductor 60, sequence switch contacts 223 (16 to 7) and (16 to 16½), left-hand back contact and armature of relay 30, and armature and back contact of relay 37 to ground (the energizing circuit of relay 37 having been interrupted at the right-hand front contact and armature of relay 30 when that relay released). As a result of the closure of this circuit, the brushes of the line-finder switch are returned to normal.

It will be noted that the circuit for energizing the down-drive magnet 62 of the line finder is not closed until relay 30 has been released as a result of the energization of relay 37, and that relay 37 is not released until the circuit by way of conductor 88 of the connecting cord circuit is closed by the complete return of the connecting cord circuit to its normal condition. As a result of this arrangement it is possible, by holding the connecting cord circuit and preventing the closure of listening key sequence switch

contact 406 (1), to hold the brushes of the line-finder switch in engagement with the terminals of the calling line, even after the act of disestablishing the connection has been initiated by the release of the holding relay 30 and the movement of the finder sequence switch out of the talking position 14. This feature is desirable where, for instance, the relay 30 of the finder circuit is accidentally released immediately after the finder circuit is extended to a connecting circuit, and before connection with the called line is completed. In this case, when the operator answers in response to the flashing of the lamp 161, she finds that the calling subscriber is not connected with the circuit, the finder sequence switch having moved out of the talking position 14 and having come to rest in position 16. As the energizing circuit of the down-drive magnet 62 of the line finder cannot be closed in position 16 until conductor 88 is closed at sequence switch contact 406 (1) by the return of the listening key sequence switch to normal, the operator is able, by holding the listening key sequence switch in position 7, to prevent the return of the line finder until the switchboard attendant has been notified and has identified the finder circuit that has failed to operate properly. When this has been done, the connection may be released and the line finder switch permitted to return to normal by causing the listening key sequence switch to move to position 1 and close, at contact 406 (1), the circuit of conductor 88. The operator may accomplish this by pressing the listening-out key 432, which closes a circuit for moving the listening key sequence switch out of position 7. The switch moves through position 15 on account of the energizing path for its motor magnet completed by way of sequence switch contact 402 (15), outer left-hand back contact and armature of relay 500, and lower back contact and armature of relay 421, and comes to rest in position 1.

As the line-finder brushes reach normal, a circuit is closed that extends from battery through the motor magnet and contact 204 (16) of the finder sequence switch, conductor 69, and Y segment and corresponding brush of the line-finder commutator to ground. When the finder sequence switch moves to position 17, as a result of the closure of the above traced circuit, a circuit is completed that extends from battery through the winding of the down-drive magnet 35 of the cord selector, conductor 90, finder sequence switch contact 218 (17), conductor 67, and M segment and corresponding brush of the line-finder commutator to ground. The closure of this circuit returns the cord selector switch to normal; and as the brushes reach normal a circuit is closed that extends from battery through the wind-

ing and contact 204 (17) of the finder sequence switch, conductor 31, and segment Y and corresponding brush of the cord selector commutator to ground. The closure of this circuit causes the finder sequence switch 200 to return to its normal or 1 position.

In the normal operation of the system the process of establishing or disestablishing a connection is as has been described in the foregoing. It may, however, occasionally happen in the operation of the system that for some reason, such as the sticking of the line relay 12 or the failure of the cut-off relay 11 to operate, that the high potential test battery which identifies the calling line is not removed from the finder switch test terminals of that line when the line is connected with. The manner in which the system is organized to care for this particular condition when it arises will now be described.

It will be remembered that when the finder switch makes connection with the calling line the sequence switch 200 is moved out of position 4, and that when the sequence switch reaches position 4 $\frac{1}{2}$, a circuit is closed by way of cam 212 and conductors 50 and 53 for energizing the cut-off relay 11 of calling line and bringing about the release 30 of the associated line relay 12. If for any reason the line relay fails to release its armatures, the high potential identifying battery 251 remains in connection with the test conductor 253 of the associated line. Consequently when the finder sequence switch moves out of position 6 upon the finder circuit gaining access to the operator's selecting circuit, a circuit is closed that extends from the high potential test battery 251, the winding of the common protective relay 250, the armature and back contact of that relay, left-hand front contact and armature of line relay 12, test conductor 253, test terminal 47 and corresponding test brush 43 of the line-finder, conductor 51, contacts 224 (1 to 8) and (6 $\frac{1}{2}$ to 8) of the finder sequence switch, conductor 260, and right-hand winding of relay 52 of the operator's selecting circuit to ground. Therefore the presence 50 of the test potential at a time when in the normal operation it should be absent, causes the energization of the delay 52. Relay 52, in operating, closes a locking circuit for itself that extends from battery through the left-hand winding of relay 52, left-hand front contact and armature of that relay, conductor 71, finder sequence switch contact 218 (6 $\frac{1}{2}$ to 8), conductor 67, and the M segment and corresponding brush of the line-finder commutator to ground. At its right-hand armature and back contact, the relay 60 opens the path over which the impulse must flow that operates the set of relays 93 and 94 corresponding with the available operator's position. Thus, when, an instant

later, the finder sequence switch reaches position 7, the ground that is applied to conductor 73 by the closure of finder sequence switch contacts 218 (7 to 8) does not pass to one or another of the sets of relays 93 and 94 by way of the armature and front contact of the corresponding relay 77; but instead is communicated to the relay 30 by way of the conductor 72. The circuit just referred to extends in one branch from battery through resistance 56, finder sequence switch contacts 217 (2 to 9), right-hand winding of relay 30, and contacts 220 (7) of the finder sequence switch to the conductor 72 and in the other branch the circuit extends from battery through the left-hand winding of relay 30, contacts 220 (1 to 13) and (7) of the finder sequence switch to the same conductor 72. Thence the circuit continues by way of the right-hand front contact and armature of relay 52, inner armature and front contact of the relay 54, back contact and armature of relay 63, back contact and armature of relay 61, conductor 73, finder sequence switch contact 218 (7), conductor 67, and segment M and corresponding brush of the line-finder commutator to ground. Relay 30 attracts its armatures and closes a circuit that extends from battery through the motor magnet and cam 202 (6 to 7) of the finder sequence switch, right-hand front contact and armature of relay 30, contact 208 (2 to 7) of the finder sequence switch, conductor 79, and segment M and corresponding brush of the cord selector 100 commutator to ground. The closure of this circuit moves the finder sequence switch to position 8. Relay 30 in operating also closes a locking circuit for itself that includes its right-hand winding and extends to ground 105 by way of contact 216 (7 to 9) and (2 to 9) of the finder sequence switch, left-hand front contact and armature of relay 30, and armature and back contact of the relay 37.

The movement of the sequence finder 110 switch to position 8 and the operation of the relay 30, closes the circuit of the cord selector up-drive magnet 34 in a manner that has already been described, and the brushes of the cord selector switch start to 115 move up. But as the energization of the relay 52 has prevented the operation of any of the sets of relays 93 and 94 of the operator's selecting apparatus, none of the trip magnets 21, 22 is actuated, and consequently 120 the sets of brushes are moved past the tripping position without any of the sets being tripped. As the tripping position is passed, the grounding of the K segment of the cord selector commutator completes the circuit 125 for energizing the relay 61 of the operator's selecting apparatus, and that relay closes the circuit by way of contacts 204 (8) of the finder sequence switch that causes the sequence switch to move out of position 8 130

and into position 9, as already described. In position 9 of the finder sequence switch the upward movement of the cord selector brushes continues. But as none of the sets 5 of brushes has been tripped to make it operative, the brush carrying rod or elevator goes to the limit of its upward movement, and there grounds the X segment of the cord selector commutator. This closes a circuit 10 that extends from battery through the motor magnet and contacts 205 (7 to 14) and (1 to 16) of the finder sequence switch (the switch being in position 9 at the time), conductor 70, and X segment and corresponding brush 15 of the cord selector commutator to ground. As a result of the closure of this circuit the finder sequence switch is moved through its positions up to and including position 14, coming to rest in position 15. 20 In position 15 of the finder sequence switch an energizing circuit is closed for both windings of the relay 30, one branch of this energizing circuit extending from battery through resistance 56, finder sequence switch 25 contacts 217 (15 to 16) and (12 to 16), right-hand winding of relay 30, and contacts 220 (15) and (11 to 16) of the finder sequence switch to conductor 67, and the other branch extending from battery through the left- 30 hand winding of relay 30, finder sequence switch contacts 220 (15) and (11 to 16) to the same conductor 67. Thence the path is to ground by way of the M segment and corresponding brush of the line-finder commutator. Relay 30, in operating, closes a circuit for itself that includes its right-hand winding and extends through finder sequence switch contacts 216 (15 to 16), left-hand front contact and armature of relay 30, and 35 40 armature and back contact of relay 37 to ground. Relay 30 in operating also closes at its right-hand front contact and armature a circuit for moving the finder sequence switch out of position 15, as previously described. 45 In both positions 15 and 16 of the finder sequence switch a circuit is completed that extends from battery through the winding of relay 255, finder sequence switch contacts 50 205 (15 to 16) and (1 to 16), conductor 70 and X segment and corresponding brush of the cord selector to ground. Relay 255 in operating closes at its upper armature and front contact an energizing circuit for the 55 lamp 257, and the illumination of the lamp indicates to the switchboard attendant that a cord selector switch is at "tell-tale"; that is, that its brushes have passed beyond the selectable contacts and are at the limit of 60 their upward movement. The attendant thereupon may inspect the cord selectors of the associated frame, note the selector switch that is at tell-tale, ascertain the number of the line upon which the brushes of the corre-

sponding line-finder are resting, and take 65 whatever action is necessary for relieving the condition of trouble on that line.

The above is under the assumption that the switch 256 is open. If the contacts of that switch are closed the operation of the 70 relay 255 when the cord selector goes to tell-tale closes a circuit that extends from battery through the winding of the down-drive magnet 62 of the associated line finder, conductor 60, finder sequence switch contacts 75 223 (16 to 6½), right front contact and armature of relay 255, and the closed contacts of switch 256 to ground. The closure of this circuit restores the line-finder to its normal position. The grounding of the Y segment 80 of the line-finder commutator when the brushes are returned moves the line-finder sequence switch out of position 16 and into position 17, the movement of the finder sequence switch into position 17 closes the 85 energizing circuit of the down-drive magnet 35 of the cord selector, and the return of the cord selector brushes to their normal position grounds the Y segment of the cord selector commutator and moves the finder 90 sequence switch to its normal or 1 position, all as has heretofore been described in connection with a normal operation of the organization.

From the foregoing it may be seen that 95 the organization is such that when, through any improper operation of the apparatus, the test potential is not removed from the calling line when that line is connected with, the finder circuit is immediately deprived of any control over the operator's selecting circuit and the corresponding cord selector switch is moved to tell-tale and a signal given the switchboard attendant, the cord selector being held at tell-tale and the associated line-finder being held on the terminals of the calling line if the switch 256 is open, and the finder circuit and switches being automatically returned to normal if the switch 256 is closed. The failure 100 of the line relay to release is thus prevented from extending the line that is in trouble to an operator's position.

In order that the features to which this invention is directed may be fully and 115 clearly disclosed, it has been necessary to describe them in connection with other features that are the subject of copending applications assigned to same assignee, such applications including the applications of S. B. 120 Williams, Jr., Serial No. 75,328, filed January 31, 1916; Serial No. 75,329, filed January 31, 1916; Serial No. 107,090, filed July 1, 1916, and the application of F. A. Stearn, Serial No. 107,540, filed July 5, 1916. Such 125 other features are the subject of claims in the applications mentioned above, and are not claimed in the present application.

What is claimed is:

1. The combination with a plurality of telephone lines, of means associated with each line for altering its electrical condition in calling, a finder circuit for making connection with a calling line, means for restoring the normal electrical condition of a calling line in establishing connection therewith, operator selecting apparatus associated with said finder circuit, a test magnet responsive to the altered electrical condition of a connected telephone line, and means controlled in the response of said test magnet for rendering said operator selecting apparatus inoperative.
2. The combination with a plurality of telephone lines, of a source of test current, means associated with each line for connecting said source with said line in calling, a finder circuit responsive to said test current for making connection with the calling line, means for disconnecting said source from said calling line in establishing connection therewith, selecting apparatus controlling a further extension of said finder circuit, a test magnet associated therewith responsive to a continuance of said current on the calling line after the finder circuit has established connection therewith, and means controlled in the response of said test magnet for rendering said selecting apparatus inoperative.
3. The combination with a plurality of finder circuits, of a plurality of operators' positions, common selecting apparatus controlling the extension of said finder circuits to said operators' positions, a test magnet associated with said common selecting apparatus for rendering the same temporarily inoperative, a source of current for operating said test magnet, and means for bringing said source into connection with said test magnet by way of any of said finder circuits when such circuit is in abnormal condition, whereby an abnormal condition of a finder circuit prevents the same from selecting an operator.
4. The combination with a plurality of telephone lines, of a plurality of operators' positions, a plurality of finder circuits for establishing connection between any line and any operator's position, common selecting apparatus controlling the extension of a finder circuit to an operator's position, a test magnet for rendering said common selecting apparatus temporarily inoperative, a source of current for operating said test magnet, and means rendered operative by an abnormal condition of any connected line for applying said source to said test magnet.
5. The combination with a plurality of operators' positions, of a plurality of circuits adapted to be extended thereto, selecting apparatus common to said circuits and

said positions, said selecting apparatus acting to control the extension of any of said circuits to any operator's position, a source of current, means operating under abnormal conditions for applying said source of current to any of said circuits, and means responsive to the application of said source of current to any said circuits for rendering said common selecting apparatus temporarily inoperative.

6. The combination with a plurality of telephone lines and a plurality of connecting circuits, of a finder circuit for establishing connection therebetween, means for preventing connection between said finder circuit and said connecting circuits, and means made operative by an abnormal condition of any connected line for operating the aforesaid preventing means.

7. The combination with a plurality of telephone lines, of a finder circuit for making connection therewith, a plurality of connecting circuits, a switch for extending the connection of said finder circuit to an idle one of said connecting circuits, means for preventing said switch from extending the connection of said finder circuit, and means for actuating said preventing means made operative by an abnormal condition of any line connected with said finder circuit.

8. The combination with a plurality of telephone lines and a plurality of connecting circuits, of a finder circuit provided with a finder switch for making connection with any of said telephone lines and a selector switch for making connection with any of said connecting circuits, a source of test current, means for applying the same to any of said lines in calling, means actuated in establishing connection with a calling line for withdrawing said source of test current, and means responsive to the continuance of said test current on a calling line after connection is made therewith for preventing said selector switch from establishing connection with any of said connecting circuits.

9. The combination with a telephone line, of a source of test current, means for connecting said source with said line in calling, a finder circuit provided with a finder switch responsive to said source of test current to establish connection with a calling line, means operated in establishing connection for disconnecting said source of test current, means for further extending said finder circuit, and means operated by the continued connection of said source with said line after the finder switch has connected therewith for preventing the operation of said circuit extending means.

10. The combination with a telephone line, of means for altering the electrical condition of the same in calling, a finder

circuit responsive to the altered condition of said calling line for making connection therewith, means operated in establishing said connection for restoring the normal 5 electrical condition of said line, a connecting circuit, means for extending said finder circuit to said connecting circuit, and means responsive to the continuation of the altered electrical condition of said line after connection is made therewith for preventing 10 the operation of said extending means.

11. The combination with a telephone line, of means for altering the electrical condition of the same in calling, a finder circuit responsive to the altered condition of 15 said calling line for making connection therewith, means operated in establishing said connection for restoring the normal electrical condition of said line, a connecting circuit, a switch for connecting said finder circuit with said connecting circuit, an emergency device, and means responsive 20 to the continuation of the altered electrical condition of said line after connection is made therewith for preventing said switch 25 from extending said finder circuit to said connecting circuit and causing it to operate said emergency device.

12. The combination with a telephone 30 line and a cord circuit, of a finder circuit, a switch for connecting said finder circuit with said telephone line, means for connecting said finder circuit with said cord circuit, a sequence switch associated with 35 and controlling said cord circuit, means actuated in connecting said finder circuit with said cord circuit for moving said sequence switch out of its normal position, and means made operative by the return of said sequence 40 switch for moving said finder switch to disconnect said finder circuit from said telephone line.

13. The combination with a telephone line and a cord circuit, of a finder circuit, 45 means for connecting said finder circuit with said telephone line, means for connecting said finder circuit with said cord circuit, a sequence switch associated with and controlling said cord circuit, means actuated in connecting said finder circuit with 50 said cord circuit for moving said sequence switch out of its normal position, means for returning said sequence switch to normal, and means made operative by the return 55 of said sequence switch for disconnecting said finder circuit from said cord circuit.

14. The combination with a calling telephone line, a connecting circuit, and a finder circuit uniting the same, of a sequence 60 switch associated with said connecting circuit, means actuated by the completion of connection between said finder circuit and said connecting circuit for moving said sequence switch out of normal, a called tele-

phone line, means for connecting said connecting circuit with said called line, a switch operated in disconnecting said connecting circuit from said called line for returning said sequence switch to normal, and means actuated by the return to normal of 70 said sequence switch for disconnecting said finder circuit from said calling line.

15. The combination with a telephone line and a connecting circuit, of a finder circuit for uniting the same, testing mechanism responsive to the normal electrical condition of said connecting circuit, means controlled thereby for causing the finder circuit to make connection with said connecting circuit means for varying the electrical condition of said connecting circuit responsive to the establishment of connection therewith, means for reestablishing the normal electrical condition of said connecting circuit, and means made operative 80 by said testing mechanism upon the reestablishment of said normal electrical condition for effecting the disconnection of said finder circuit from said telephone line.

16. The combination with a connecting 90 circuit, of a finder circuit, an electromagnetic switch for establishing connection between said finder circuit and said connecting circuit, a test magnet controlling the operation of said switch, said test magnet 95 being responsive to the normal electrical condition of said connecting circuit, means operating to vary the electrical condition of said connecting circuit upon the establishment of connection therewith, means for restoring the normal electrical condition of said connecting circuit, and means for operating said electromagnetic switch to disconnect said finder circuit from said connecting circuit, said means being actuated 100 through the agency of said test magnet upon the restoration of the normal electrical condition of said connecting circuit.

17. The combination with a plurality of telephone lines and a plurality of cord circuits, of a finder circuit provided with an electromagnetic line-connecting switch, and an electromagnetic cord-connecting switch, means for varying the electrical condition of any of said lines and of any of said cords, 110 a test magnet associated with said finder circuit, means controlled by said test magnet in response to the changed electrical condition of a line for causing said line-connecting switch to establish connection therewith, means controlled by said test magnet 115 in response to the normal electrical condition of a cord for causing said cord-connecting switch to establish connection therewith and vary the electrical condition of the 120 same, means for reestablishing the normal electrical condition of the cord, and means controlled by said test magnet in response 125

- to the reestablishment of the normal electrical condition of said cord for operating said line-connecting switch to disconnect said finder circuit from said telephone line.
- 5 18. The combination with a plurality of telephone lines and a plurality of cord circuits, of a finder circuit provided with an electromagnetic line-connecting switch and an electromagnetic cord-connecting switch,
- 10 means for operating said switches and causing the same to connect respectively with one of said lines and one of said cords, a holding magnet associated with said finder circuit for maintaining the continuity of
- 15 said finder circuit, means for releasing said holding magnet to break the continuity of said finder circuit, means operable after said holding magnet is released for restoring said line-connecting switch and said
- 20 cord-connecting switch, and a switch associated with said cord circuit for actuating said means.
19. The combination with a plurality of operators' positions and a plurality of finder
- 25 circuits, of operator's selecting apparatus common to said positions and said circuits, a selector switch for each finder circuit, means set by said operator's selecting circuit for controlling the selective operation
- 30 of any of said selector switches, means for moving each selector switch, means operated in the setting of said operator's selecting apparatus for energizing the moving means of one of said selector switches, and means
- 35 for delaying the energization of said moving means for a predetermined interval after the setting of said selecting apparatus.
20. The combination with a plurality of connecting circuits, of a test conductor for
- 40 each of said circuits, a connecting switch for making connection with any of said circuits said connecting switch being responsive to the normal condition of the test conductor of any of said circuits, a sequence switch
- 45 associated with each connecting circuit for altering the normal electrical condition of the associated test conductor when said connecting switch makes connection with said connecting circuit, and an electromagnetic switch operated by the establishment
- 50 of connection with any of said connecting circuits for altering the electrical condition of the test conductors of all of said connecting circuits in advance of the operation of
- 55 said sequence switch when connection is established with any of said connecting circuits.

21. The combination with a plurality of connecting circuits, of operator's telephone
- 60 apparatus common to said circuits, a test conductor for each of said circuits, a switch responsive to the normal electrical condition of the test conductor of any of said circuits for making connection therewith, electri-

cally actuated mechanism responsive to the 65 establishing of connection with any of said circuits for altering the electrical condition of the associated test conductor and connecting said operator's telephone apparatus with said circuit, an electromagnetic switch for 70 changing the electrical condition of the test conductors of all of said circuits, and means actuated upon the establishing of connection with any of said circuits for operating said electromagnetic switch in advance of the 75 operation of the aforesaid electrically actuated mechanism.

22. The combination with a plurality of circuits, of a switch for making connection with any of said circuits, means individual 80 to each of said circuits for rendering the associated circuit unselectable upon the establishment of connection therewith, and means common to all of said circuits for rendering all of the circuits temporarily 85 unselectable upon establishment of connection with any one of them and in advance of the operation of said individual means.

23. The combination with a plurality of connecting circuits, of a switch for making 90 connection therewith, operator's telephone apparatus common to said circuits, mechanism individual to each circuit for making the same unselectable and bringing the operator's telephone apparatus into connection 95 therewith when connection is made with said circuit, means common to all of said circuits and operating in advance of the operation of said mechanism for rendering all of said circuits unselectable when connection is es- 100 tablished with any one of them, and means operated by said mechanism for reestablishing the selectability of all of said connecting circuits excepting the one with which connection has been established.

24. The combination with a group of connecting circuits of a test conductor for each circuit, means for making connection with any of said connecting circuits responsive to the electrical condition of the associated test 110 conductor of that circuit, an individual switch controlling the electrical condition of each test conductor, a common switch controlling the electrical condition of all of the conductors of the group, means made operative in establishing connection with any of said connecting circuits for actuating said common switch and the individual switch of the circuit, and a timing switch for controlling the period of actuation of said common switch.

25. The combination with a plurality of operators' positions, of a plurality of connecting circuits at each operator's position, a plurality of finder circuits, operator's selecting apparatus common to said positions and said circuits and controlling the selection of a position by a finder circuit, means

individual to each connecting circuit for rendering the same unselectable by other finder circuits when one of said finder circuits establishes connection therewith, means common to all of said connecting circuits for rendering all temporarily unselectable when connection is made with any one of them, said common means being operated in

advance of said individual means, and means actuated in the operation of said 10 common means for rendering the corresponding operator's position unselectable.

In witness whereof, I hereunto subscribe my name this 13th day of July A. D., 1917.

SAMUEL B. WILLIAMS, JR.
